CLAIM

The ornamental design for a pressure washer, as shown and described.

DESCRIPTION

FIG. 1 is an isometric view of the pressure washer, and further illustrating a bucket thereon;

FIG. 2 is an isometric view thereof, without the bucket;

FIG. 3 is a rear view thereof;

FIG. 4 is a front view thereof;

FIG. 5 is a right side view thereof;

FIG. 6 is a left side view thereof;

FIG. 7 is a top view thereof;

FIG. 8 is a bottom view thereof; and,

FIG. 9 is a bottom isometric view thereof.

The dashed line showing of a bucket in FIG. 1 represents an exemplary environment and forms no part of the claimed design. The other dashed lines in the Figures depict portions of the pressure washer that form no part of the claimed design.
